A. POIRIER

INDICATOR

Filed Aug. 21, 1922

UNITED STATES PATENT OFFICE.

ALPHONSE POIRIER, OF SPOKANE, WASHINGTON.

INDICATOR.

Application filed August 21, 1922. Serial No. 583,074.

To all whom it may concern:

Be it known that I, ALPHONSE POIRIER, a citizen of the United States, residing at Spokane, in the county of Spokane and 5 State of Washington, have invented certain new and useful Improvements in Indicators, of which the following is a specification.

This invention relates to indicators for 10 exhibiting the price of merchandise, and designed to take the place of the usual tags ordinarily employed for this purpose.

The invention has for its object to provide 15 a novel and improved indicator for the purpose stated, which is provided with a changeable reading so that the information to be displayed may be readily changed.

The invention also has for its object to 20 provide an indicator of the kind stated which is durable and practical, and simple in construction.

A further object of the invention is to 25 provide an indicator in which the reading matter to be displayed can be changed without removing the device from the shelf or other support on which it is mounted.

With the objects stated in view, the invention consists in a combination and arrangement of parts to be hereinafter described and claimed, and in order that the same may be better understood, reference is had to the accompanying drawing, wherein—

Figure 1 is a front elevation of the device; Fig. 2 is a horizontal section thereof; Fig. 3 is an enlarged cross section on the line 3—3 of Fig. 1; Figs. 4, 5 and 6 are plan views of the indicator belts; Fig. 7 is a perspective view of the device showing an auxiliary indicator element, and Fig. 8 is 40 a rear elevation of a device showing a pin fastener associated therewith.

Referring specifically to the drawing, the device consists of a supporting frame carrying a number of charactered belts of paper, celluloid or other suitable material, having their ends connected to rollers so that they may be wound on one roller as they are unwound from the other for selectively displaying the characters thereon. In the present instance, three belts are used, but their number is immaterial and may be varied according to the information to be displayed. The belts are denoted by the reference characters 10, 11 and 12, respectively, and each belt is connected at its ends to a

roller 13. The supporting frame of the device is a base plate 14 across the face of which the belts are trained, and in order to protect the latter from dirt, flies, dust and the like, a strip 15 of mica or similar transparent material is provided beneath which the belt is located, said strip being removably attached to the base plate by small tongues 16 struck out from the same. The base plate 14 has rearwardly directed top and bottom flanges 17 and 18, whereby the device may be mounted on the edge of a shelf denoted by dotted lines at 19 in Fig. 3. The bottom flange has an upward curve and is resilient, so that when the two flanges are forced over the edge of the shelf, they will grip the same and firmly hold the device in place. The extremity of the bottom flange is also provided with two laterally spaced rolls 20 which are in longitudinal alignment and serve to hold a pin 21 having its shank provided with two diverging resilient branches 22 the extremities of which have outward lateral bends 23. Upon squeezing the branches 22 together and placing them between the opposed ends of the rolls 20 so as to bring the bends 23 in line with the latter, and then releasing the branches, they spread and the bends 23 enter the rolls. The pin 21 is now securely anchored to the device, and by means of said pin the device may be stuck into any article such as a piece of cheese, meat or anything else that is not kept on a shelf or in boxes. Where goods are kept on a shelf or a table, or in a box, the flanges 17 and 18 will be employed for attaching the device to such shelf or box by slipping said flanges over the edge thereof. It will be understood, of course, that when the device is applied to a shelf it will be positioned directly in front of the article the price of which it is to indicate.

Each roller 13 is in the shape of a split pin provided with a flat head 24 at one end, and having the free ends of its branches bent laterally as shown at 25. The ends of the belts are clamped between the branches of the pins. In parallel portions of the flanges 17 and 18, adjacent to the base plate 14, are alined apertures in which the pins seat, the heads 24 being beneath the bottom flange, and the bends 25 above the top flange to prevent the pins from becoming separated from the flanges. The pins are located behind the base plate 14, and the end belts pass around the ends of said plate and

2
through vertical slots 26 in the plate intermediate the ends thereof. The intermediate belt also passes through the slots 26.

The belt 10 is shown provided with the characters "0" to "9"; $\frac{1}{2}$, "each", "Doz.", "Yd.", "Pound" and "For". The belt 11 contains the characters "0" and "1" to "9" with a decimal point before the same. The belt 12 contains the characters "0¢", "1¢" 10 and so up to "9¢". By this arrangement of characters the belts can be adjusted to display a large variety of information, as for instance, the price of a yard of goods, a single article, a dozen, or a pound. The 15 portions of the belts which are displayed come closely together at their adjacent ends so that the inscriptions can be easily read.

At 27 is shown an auxiliary indicator element consisting of a strip having rearwardly directed top and bottom flanges 28 adapted to be slipped over the flanges 17 and 18 to position the strip vertically in front of the exposed or display portions of the belts. This strip contains the inscription "For", 25 and it may be placed between the adjacent ends of the belts 10 and 11, as shown in Fig. 7 so that the indicator now displays the cost of a certain number of articles. Similar strips may be 30 provided containing the inscriptions "Doz." and "Yds."

It will be evident from the foregoing that the invention provides a simple and practical price indicator, and while the preferred structure has been disclosed, it will be understood that various changes and modifications may be made without a departure from the spirit and scope of the invention as claimed hereinafter. The characters or 35 inscriptions on the belts can be arranged in various ways, and others may be provided according to the character of the business and the nature of the articles with which 40

the device is to be associated. The frame of the device may be made of sheet metal 45 celluloid or any other suitable material.

I claim:

1. An indicator comprising a base plate having rearwardly directed top and bottom flanges, characterized belts extending across the face of the base plate, rollers to which the ends of the belts are connected, said rollers being located behind the base plate between the aforesaid flanges and journaled therein, and an auxiliary indicator member comprising a characterized strip adapted to be positioned across the exposed portions of the belts and having top and bottom retaining flanges engageable with the first-mentioned flanges. 55

2. An indicator comprising a base plate having rearwardly directed top and bottom flanges, the bottom flange having its extremity provided with a pair of laterally spaced rolls, a supporting pin having its shank provided with a pair of resilient diverging branches having lateral bends at their extremities adapted to be removably inserted into the rolls, characterized belts extending across the face of the base plate, and rollers 65 to which the ends of the belts are connected, said rollers being located behind the base plate between the aforesaid flanges and journaled therein.

3. An indicator comprising a support, 75 characterized belts extending across the face thereof, rollers carried by the support, the ends of the belts being connected to the rollers, and an auxiliary indicator member comprising a characterized strip adapted to be 80 positioned across the exposed portions of the belts, said strip being carried by the support.

In testimony whereof I affix my signature.

ALPHONSE POIRIER.
